United States Patent Office

Des. 219,726
Patented Jan. 19, 1971

219,726

SKI SHARPENER

Edward E. van Horn, 15 Hadley St.,
Armonk, N.Y. 10504

Filed Nov. 3, 1969, Ser. No. 19,910

Term of patent 14 years

Int. Cl. D8—02

U.S. Cl. D8—91

FIG. 1 is a top plan view of a ski sharpener showing my new design;

FIG. 2 is a side elevational view thereof;

FIG. 3 is an end elevational view thereof;

FIG. 4 is a bottom plan view thereof;

FIG. 5 is a perspective view thereof, on a reduced scale.

I claim:

The ornamental design for a ski sharpener, substantially as shown.
